UNITED STATES PATENT OFFICE.

VOLLIE B. MARRS, OF SANTA ANNA, TEXAS, ASSIGNOR OF ONE-HALF TO D. J. HARRIS, OF SANTA ANNA, TEXAS, AND ONE-EIGHTH TO WILLIAM HENRY BLAKEY, OF BUCKHOLTZ, TEXAS.

STEAM-BOILER INDICATOR.

1,095,012.

Specification of Letters Patent. Patented Apr. 28, 1914.

Application filed July 18, 1913. Serial No. 779,862.

To all whom it may concern:

Be it known that I, VOLLIE B. MARRS, a citizen of the United States, residing at Santa Anna, in the county of Coleman and State of Texas, have invented new and useful Improvements in Steam-Boiler Indicators, of which the following is a specification.

This invention relates to improvements in steam boiler indicators and has particular application to a combination steam pressure and water level indicator.

In carrying out the present invention, it is my purpose to provide a device of the class described whereby when the water level within the boiler has dropped below a predetermined point, a signal will be given so as to advise the engineman of the condition of the water and by means of which an alarm will be sounded in the event of the steam pressure exceeding a predetermined point or dropping below such point.

It is also my purpose to provide a device of the class described whereby the signals for indicating the increase and decrease in the steam pressure and the fall of the water level will have relatively different tones so that the engineman will be advised as to the proper course to pursue without resorting to the usual tests.

Furthermore, I aim to provide a steam boiler indicator whereby a signal will be given when the water within the boiler falls below a predetermined level and by means of which a second signal will sound when such level has been restored to normal so that the engineman will be notified when to cut out the pump or injector.

A further object of the invention is the provision of a steam boiler indicator which will embrace the desired features of simplicity, efficiency and durability, one which will operate at all times for its various purposes and one which may be readily applied to any type of steam boiler without resorting to changes or alterations in the boiler structure.

With the above and other objects in view, the invention consists in the construction, combination and arrangement of parts hereinafter set forth in and falling within the scope of the claims.

In the accompanying drawings; Figure 1 is a view in elevation of a steam boiler indicator constructed in accordance with my present invention. Fig. 2 is a vertical central sectional view through the same. Fig. 3 is an enlarged fragmentary sectional view through the upper portion of the indicator showing the water level signals. Fig. 4 is an enlarged plan view of one of the controlling valves of the indicator. Fig. 5 is a similar view of an actuating device for the controlling valve. Fig. 6 is a fragmentary sectional view on the line 6-6 of Fig. 2 looking in the direction of the arrow. Fig. 7 is a similar view on the line 7-7 of Fig. 2 looking in the direction of the arrow.

Referring now to the accompanying drawings in detail, the numeral 1 designates a casing or housing composed of any suitable material and preferably, although not necessarily, of cylindrical outline in cross section and having its upper and lower ends closed through the medium of caps 2 and 3 preferably cup shaped and having the inner surfaces of the side walls thereof threadedly engaging the adjacent ends of the casing. This casing 1 is divided into a number of compartments, three being shown in the present instance at 4, 5 and 6, partitions 7 within the body 1 and suitably spaced apart separating the chambers.

In the present instance, the chambers 4 and 5 are adapted to have communication with each other under certain conditions and for this purpose the respective partition 7 is provided with a nipple 8 depending a short distance into the chamber 5 and carrying at its lower end a valve casing in which is rotatably mounted a valve and connected to the stem of such valve is a handle 95 10 to the free end of which is fastened through the medium of a pin and slot connection 11 a depending link 12 having the lower end thereof fastened to a float 13 disposed within the chamber 5 and equipped 100 on its under surface with a weight 14. Leading into the chamber 5 adjacent to the top and bottom ends thereof are nipples 15, 16, the former being adapted to have communication with the steam space of a boiler 105 while the latter is designed to communicate

with the water space thereof, so that under normal conditions, the float 13 will be balanced and maintain a position approximately centrally of the height of the chamber 5 whereby the valve within the casing 9 will be held closed.

Arranged within each chamber 4, 6 and adapted for sliding movement therein is a piston 17 and interposed between the upper 10 surface of each piston and the cap 2 of the respective partition 7 of the chambers 4 and 6 respectively is a coiled expansion spring 18 acting normally to hold the pistons at their limit of downward movement. Passed 15 through the side wall of the upper chamber 4 adjacent to the bottom thereof is a pipe 19 equipped at its outer end with an audible signal in the present instance in the form of a whistle 20 and having the inner end thereof 20 provided with a controlling valve 21 which in this embodiment of my invention comprises an annular disk 22 formed with an outwardly projecting concentrically disposed flange 23 threaded interiorly to receive the inner end of the pipe 19, the central portion of the disk 22 being provided with an aperture 24 coaxial with the pipe 19. Pivotally mounted on the outer face of the disk 22 at diametrically opposite points 25 are sector-like plates 25, 26 having the inner ends thereof overlapping each other and the outer or relatively small ends projecting beyond the periphery of the disk 22, as clearly illustrated in Fig. 4. These sector-shaped 30 plates 25 and 26 are adapted for swinging movement in a vertical plane and the path of movement of the plate 26 is preferably greater than that of the plate 25. Each plate 25, 26 is formed with a segmental slot 35 35 40 45 50 55 60 65 70 75 80 85 90 95 100 105 110 115 120 125 130

instance, of an arm 32 carrying at its lower end a yoke 33 having a short arm 34 and a relatively long arm 35 each provided with a laterally projecting pin 36 at its lower end. The pin 36 on the short arm 34 is normally disposed below a spring dog 37 on the relatively small end of the sector-like plate 25, while the pin 36 on the arm 35 is similarly located with respect to a spring dog 38 on the relatively small end of the sector-like plate 26. Extending outwardly of the side wall of the chamber 4 at a point diametrically opposite the pipe 19 is a second pipe 39 having the inner end thereof equipped with a valve 40 provided with a handle 41 connected through the medium of a pin and slot connection 42 with a depending link 43 having the lower end thereof suitably secured to the handle 10 of the valve within the casing 9. The outer end of the pipe 39 is equipped with a signal, in the present instance, preferably in the form of a whistle 44. A water glass 45 is suitably fastened to the side wall of the chamber 5 at a point diametrically opposite the nipples 15 and 16 and has communication with such chamber through suitable connections.

The operation of the signals 20 and 44 may be briefly described as follows: When the water within the boiler is at its normal level the float 13 maintains a position approximately centrally of the chamber 5, being balanced on the water on the under side and the steam on the upper side, and so holds the valve within the casing 9 in closed position thereby cutting off communication between the chambers 4 and 5. When the level of the water within the boiler drops below normal, the float 13 descends and so opens the valve within the casing 9 thereby permitting the steam to pass from the steam space of the boiler through the nipple 8 and into the upper portion of the chamber 5 and thence through the nipple 8 into the chamber 4 below the piston 17 therein. As the steam enters the chamber 4, such steam acts upon the lower face of the piston 17 to force the latter upwardly within the chamber 4 and against the action of the spring 18. As the piston 17 moves upwardly within the chamber 4, an actuating device consisting of the arm 32 and the yoke 33 is similarly moved and the pin 36 on the arm 35 of the yoke engages the dog 38 on the relatively small end of the sector-like plate 26 thereby swinging the latter about its pivotal connection with the disk 22 to bring the opening 30 therein into registration with the aperture 24 in the disk. Subsequent to the swinging movement of the plate 26 to bring the apertures 30 and 24 into registration, the pin 36 on the end of the arm 34 of the yoke engages the dog 37 of the plate 25 and swings the latter about its pivotal connection with the disk 22 to bring the aperture 29 in such 130

Depending from the piston 17 within the chamber 4 and suitably secured thereto is an actuating device composed, in the present

plate into registration with the alining apertures 24 and 30. Thus, the steam within the chamber 4 is permitted to pass through the whistle 20 by way of the pipe 19 and so sound the alarm, the tone of the whistle 20 advising the engineman that the water within the boiler has dropped below the normal level. Having been thus advised, the engineman will, of course, put the pump or injector 10 into service to restore the water level to normal and as the water rises within the boiler the float 13 is elevated to close the valve within the casing 9 and so shut off the flow of steam into the chamber 4. When 15 the flow of steam within the chamber 4 is cut off, the spring 18 reacts and so forces the piston 17 downwardly. As the valve within the casing 9 closes, motion is imparted to the valve 40 through the medium of the link 20 42 and handle 41 to open the latter valve whereby the steam will be forced out of the chamber 4, under the action of the piston 17, and spring 18, and through the whistle 44, thereby sounding the latter and notifying 25 the engineman that the water level within the boiler has been restored to normal. In the downward movement of the piston 17 under the action of the spring 18, the pins 30 36 carried by the arms 34 and 35 of the yoke 33 idle over the spring dogs 37 and 38 thereby permitting the controlling valve 21 to remain inactive in the downward movement of the actuating device, it of course being understood that the springs 31, 31 restore the 35 sector-like plates 25 and 26 of the controlling valve to normal position after the piston 17 has been elevated within the chamber 4 a certain distance.

Extending outwardly through the side 40 wall of the chamber 6 at diametrically opposite points are pipes 46, 47 equipped at their outer ends with whistles 48, 48 of relatively different tones. The inner end of each pipe 46 is projected downwardly within the chamber 6, as clearly illustrated in Fig. 45 2 of the drawings, and has slidably mounted thereon an angular pipe 49 having the vertical limb thereof provided with an outwardly extending guide shoe 50 designed to slide 50 within a guideway 51 suitably secured to the inner wall of the chamber below the respective pipe. Swiveled or otherwise connected to the horizontal member of each angular pipe 49 is a regulating screw 52 threadedly 55 engaging the wall of an aperture 53 formed in the lower cap 3 and equipped, exteriorly of such cap, with a manipulating head 54. Mounted upon the free end of the horizontal limb of each pipe 49 is a controlling valve 55, the controlling valve on the pipe 49 connected to the pipe 47 being identical in construction to the valve 21 hereinbefore described, while the valve on the pipe 49 connected to the pipe 46 is constructed similarly 60 to the other valve 55 but has the apertures 29

and 30 in the sector-like plates 25 and 26 respectively disposed below one another and the aperture 24 so that communication will be established between the chamber 6 and the whistle 48 on the pipe 46 when the relatively large ends of the sector-like plates of the valve swing upwardly. Depending from the piston 17 within the chamber 6 are actuating devices 56, 57, each of a construction identical to that of the actuating device 70 hereinbefore described. The actuating device 56 is designed to operate the valve 55 controlling the pipe 46 on the up stroke of the piston 17, while the device 57 actuates the respective valve on the down stroke of 75 such piston. These whistles 48, 48 are designed to sound an alarm in accordance with the fluctuations of the steam pressure within the boiler and the cap 3 is provided with a depending nipple 58 adapted to be connected to the steam space of the boiler so that the chamber 6 will be in communication with such space and the piston 17 held in normal position against the action of the spring 18. Should the steam pressure within the boiler fall below the predetermined number of pounds, the piston 17 within the chamber 6 will move downwardly under the action of the spring 18 and the actuating device 57 operate the valve 55 controlling 80 the flow of steam through the pipe 47 whereby the steam will pass through the pipe 47 and into the whistle 48 and sound the latter so as to warn the engineman. On the contrary, should the steam pressure rise, the piston 17 will move upwardly against the action of the spring 18 and the actuating device 56 open the valve 55 with the effect to place the whistle 48 in communication with the chamber 6 by way of the pipe 46. Thus, the 85 engineman will be advised as to the steam pressure. A suitable pressure gage 59 is preferably tapped onto the chamber 6 so that the pressure within the boiler may be at all times ascertained.

From the foregoing description taken in connection with the accompanying drawings, the construction, mode of operation and manner of employing my invention will be readily apparent. It will be seen that I 100 have provided a steam boiler indicator whereby the engineman will be automatically advised when the water within the boiler falls below the predetermined level, whereby a signal will be given when the 105 water level has been restored to normal, and whereby the engineman will be advised when the pressure of the steam within the boiler has increased or decreased.

While I have herein shown and described 110 one preferred form of my invention by way of illustration, I desire to have it understood that I do not limit or confine myself to the precise details of construction herein described and delineated, as modification 115 120 125 130

and variation may be made within the scope of the claims without departing from the spirit of the invention.

I claim:

- 5 1. A steam boiler indicator comprising a casing divided into a plurality of compartments, means adapted to establish communication between certain of said compartments, means establishing communication between one of said intercommunicating compartments and the boiler above and below the water line therein, means in said last compartment and controlled by the water level therein to operate said first means whereby communication between said compartments will be established when the water level falls below normal, and an audible signal controlled from the other of said intercommunicating compartments and adapted to be sounded by the steam entering the last-named compartment when said first means is open.
- 10 2. A steam boiler indicator comprising a casing divided into a plurality of compartments, means adapted to establish communication between certain of said compartments, means establishing communication between one of said intercommunicating compartments and the boiler above and below the water line therein, means in said last compartment and controlled by the water level therein to operate said first means whereby communication between said compartments will be established when the water level falls below normal, an audible signal controlled from the other of said intercommunicating compartments and adapted to be sounded by the steam entering the last-named compartment when said first means is open.
- 15 3. A steam boiler indicator comprising a casing divided into a plurality of compartments, means adapted to establish communication between certain of said compartments, means establishing communication between one of said intercommunicating compartments and the boiler above and below the water line therein, means in said last compartment and controlled by the water level therein to operate said first means whereby communication between said compartments will be established when the water level falls below normal, an audible signal controlled from the other of said intercommunicating compartments and adapted to be sounded by the steam entering the last-named compartment when said first means is open, and a second signal controlled from the last-named compartment and adapted to sound when said first means has closed subsequent to the opening thereof.
- 20 4. A steam boiler indicator comprising a casing divided into three compartments, means adapted to establish communication between certain of said compartments, means establishing communication between one of said intercommunicating compartments and the boiler above and below the water line therein, means in said last compartment and controlled by the water level therein to operate said first means whereby communication between said compartments will be established when the water level falls below normal, an audible signal controlled from the other of said intercommunicating compartments and adapted to be sounded by the steam entering the last-named compartment when said first means is open, audible signals controlled from the remaining compartment, a connection between said last compartment and the steam space of the boiler, and means controlling communication between said signals and the respective chamber and adapted to place the signals in communication with the chamber in accordance with the pressure within the boiler.
- 25 5. A steam boiler indicator comprising a casing divided into a plurality of compartments, means adapted to establish communication between certain of said compartments, means establishing communication between one of said intercommunicating

compartments and the boiler above and below the water line therein, means in said last compartment and controlled by the water level therein to operate said first means whereby communication between said compartments will be established when the water level falls below normal, an audible signal controlled from the other of said intercommunicating compartments and adapted to be sounded by the steam entering the last-named compartment when said first means is open, a second signal controlled from the last-named compartment and adapted to sound when said first means has closed subsequent to the opening thereof, and means controlling communication between said last-named signal and compartment and operated from said first means.

4. A steam boiler indicator comprising a casing divided into three compartments, means adapted to establish communication between certain of said compartments, means establishing communication between one of said intercommunicating compartments and the boiler above and below the water line therein, means in said last compartment and controlled by the water level therein to operate said first means whereby communication between said compartments will be established when the water level falls below normal, an audible signal controlled from the other of said intercommunicating compartments and adapted to be sounded by the steam entering the last-named compartment when said first means is open, audible signals controlled from the remaining compartment, a connection between said last compartment and the steam space of the boiler, and means controlling communication between said signals and the respective chamber and adapted to place the signals in communication with the chamber in accordance with the pressure within the boiler.

In testimony whereof I affix my signature in presence of two witnesses.

VOLLIE B. MARRS.
